Inventor:
Wilhelm Oehm
By his attorney,
Orze Ottages

UNITED STATES PATENT OFFICE.

WILHELM OEHM, OF DUSSELDORF, GERMANY.

METHOD AND DEVICE FOR THE PRODUCTION OF HIGH TEMPERATURES.

Application filed September 20, 1921. Serial No. 502,097.

To all whom it may concern:

Be it known that I, WILHELM OEHM, a citizen of the German Republic, residing at Dusseldorf, Germany, have invented certain new and useful Improvements in Methods and Devices for the Production of High Temperatures, of which the following is a specification.

This invention relates to furnaces for the production of high temperatures and designed specially to enable the combustion of inferior fuel. Such inferior fuels could be burnt hitherto only when the natural high chimney draught was increased by producing, with the aid of exhausting devices, ventilators or steam jet blowers, a forced draught under the grate, in order to intensify the combustion process. Such arrangements suffer, however, from the drawback that the gases when escaping through the chimneys or smoke stacks are not completely consumed, and there is consequently a great waste of fuel. The use of heat accumulators heretofore proposed is not sufficient to ensure the complete combustion of inferior fuels. Also a drawback connected with the methods of combustion used at present is that it takes a long time to produce the full heating capacity of the furnace. These objections are avoided by the method and apparatus of this invention.

In the accompanying drawing two forms of construction of furnaces for the utilization of this invention are illustrated.

Fig. 1 shows, in longitudinal section, a heating furnace or melting furnace. Fig. 2 is a horizontal section of the same on line II-II of Fig. 1. Fig. 3 shows in longitudinal section a drying oven. Fig. 4 is a cross section on line IV-IV of Fig. 3.

In an oven or furnace 1 of convenient type, such as may be used, for instance, for the heating of metallic parts or for the melting of metals, burners 3 are arranged in proximity to the chamber 2 for the materials to be heated, said burners having arrow-shaped slots 4. A tube 5 inserted into the oven serves for connecting a conduit for compressed air with the oven. This tube 5 is serpentine shaped or coiled at 6 in a heated chamber above and in close proximity to the burners 3, and it terminates in the shape of a thin nozzle 7 in each of the burners 3. The arrow-shaped or converging slots 4, communicating with the combustion chambers above the grates 8, ensure perfect

combustion of the gases under the forced draft resulting from the compressed air introduced to the burners through the tube or pipe 5.

The combustion chambers above the grates 8 for supporting the solid fuel are provided with charging openings 9. A flue 10 for the waste gases connects the end of the chamber 2 with a zig-zag shaped flue 11 which communicates with the atmosphere. The zig-zag course of the gases and the outlet to the atmosphere or open air is indicated by the arrows in Fig. 2. A zig-zag shaped channel for the air for combustion is formed by the special arrangement of the walls of flue 11. The course of the air circulation to the ash-pit under the grates 8 is denoted by the arrows in Fig. 2. The air for combustion is admitted into the oven through the inlet 13 of the channel 12 so as to flow through this channel to the ash-pit under the grates, and thence upward to the combustion chambers above the grates. The heated incoming air is sucked into the combustion chambers by the forced draft induced by the compressed air admitted to the burners 3 through the pipe or pipes 5. Small holes 20 serve for admitting part of the air for combustion over the grates to the combustion chambers.

The operation of the apparatus is as follows:

The flames and the gases from the combustion of fuel on the grates 8 are forced through the slots 4 of the burners 3 by the action of the fine jet of compressed air projected from the nozzles 7 in the direction of the longitudinal axis of the burners 3 so that said gases are completely consumed, whereupon the products of combustion are forced into the chamber 2 where they are utilized for heating the materials at high temperatures. The waste products of combustion escape through the flue 10 and the zig-zag shaped flue 11 into the atmosphere, or they may be conducted to any other point in order to be further utilized, this being possible as they are still under a certain pressure.

In travelling through the zig-zag shaped flue 11 the products of combustion give up part of their heat to the walls of the flue, so that the inflowing air for combustion, passing by said walls, is thus preliminarily heated, as is also the compressed air entering to the burners through the pipe 5.

An essential advantage of this arrange-

ment consists in the fact that the furnace is heated to the required temperature shortly after the compressed air has been injected, and that the chimney flue may be contracted 5 and the draft suppressed as the gases have been thoroughly consumed, so that they can escape through a small or simple pipe.

Owing to this invention it is possible to 10 completely consume inferior fuel such as moist, mouldy raw lignite or the like, without explosions and without the production of dense smoke which are otherwise liable to occur.

Figs. 3 and 4 represent a drying oven 15 for foundry purposes and the like which works according to the improved method. The flames and the gases from combustion resulting from the combustion of the fuel upon the grate 14 are forced to flow through 20 the inclined slots 17 of a burner 18 by the forcing action of the jet of compressed air coming out of the narrow nozzle 16 of tube 15. The gases are conducted into the mould to be dried through the outflow flue 19.

25 I claim:—

1. In a heating furnace for consuming solid fuel, the combination with a grate to support said fuel and above which grate is a combustion chamber, of a burner communicating with said combustion chamber and constructed with communicating arrow-shaped or converging slots, a heating chamber with which said burner communicates, and a pipe for admitting compressed air to 30 said burner, said pipe terminating in a discharge nozzle centrally disposed relative to said converging slots.

2. In a heating furnace for consuming solid fuel, the combination with a grate to 40 support said fuel and above which grate is a combustion chamber, of a burner communicating with said combustion chamber and constructed with communicating arrow-

shaped or converging slots, a heating chamber with which said burner communicates, a 45 pipe for admitting compressed air to said burner, said pipe terminating in a discharge nozzle centrally disposed relative to said converging slots, and means for heating the compressed air thus discharged to said 50 burner.

3. In a heating furnace for consuming solid fuel, the combination with a grate to support said fuel and above which grate is a combustion chamber, of a burner communicating with said combustion chamber and constructed with communicating arrow-shaped or converging slots, a heating chamber with which said burner communicates, a pipe for admitting compressed air to said 60 burner, said pipe terminating in a discharge nozzle centrally disposed relative to said converging slots, means for heating the compressed air thus discharged to said burner, and a zig-zag passageway from said 65 heating chamber to a discharge opening, and serving to heat a flue for incoming air for combustion.

4. In a heating furnace for consuming solid fuel, the combination with a grate to 70 support said fuel and above which grate is a combustion chamber, of a burner communicating with said combustion chamber and constructed with communicating arrow-shaped or converging slots, a heating chamber with which said burner communicates, a pipe for admitting compressed air to said 75 burner, said pipe terminating in a discharge nozzle centrally disposed relative to said converging slots, means for heating the compressed air thus discharged to said burner, and a heated zig-zag passageway through which fresh air for combustion is sucked to said combustion chamber.

In testimony whereof I affix my signature.

WILHELM OEHM.
